UNITED STATES PATENT OFFICE.

EMERSON D. VERITY, OF PORTLAND, MICHIGAN, ASSIGNOR OF ONE-HALF
TO NEWEL GRIFFIN AND ELIZABETH CAMPBELL, OF SAME PLACE.

DESIGN FOR AN UMBRELLA-HOLDER.

SPECIFICATION forming part of Design No. 24,087, dated February 12, 1895.

Application filed November 28, 1894. Serial No. 530,051. Term of patent 7 years.

To all whom it may concern:

Be it known that I, EMERSON D. VERITY, a citizen of the United States, residing at Portland, in the county of Ionia and State of Michigan, have invented and produced a new and original Design for Umbrella-Holders, of which the following is a specification, reference being had therein to the accompanying drawing.

- 10 The drawing shows a perspective view of my new design for umbrella holders.
A is a rectangular base, supported on legs B at the corners.
C is a serpentine standard rising from the 15 rear side of the base at the middle thereof.
D D' are two oppositely arranged semi-circular or crescent shaped arms arranged at different heights near the top of the standard.

The top of the standard has the inclined face E, from which rise the spindles F capped 20 by the cylindrical cross bar G having knobs or balls formed at the ends.

The leading features of the design are those above described and shown in the drawing.

What I claim as my invention is— 25
The design for an umbrella holder herein described and shown.

In testimony whereof I affix my signature in presence of two witnesses.

EMERSON D. VERITY.
